UNITED STATES PATENT OFFICE.

LOUIS E. WARD, OF MIDLAND, MICHIGAN, ASSIGNOR TO THE DOW CHEMICAL COMPANY, OF MIDLAND, MICHIGAN, A CORPORATION OF MICHIGAN.

ELECTROLYTIC CELL.

1,365,875.

Specification of Letters Patent. Patented Jan. 18, 1921.

Application filed December 13, 1918. Serial No. 266,616.

To all whom it may concern:

Be it known that I, LOUIS E. WARD, a citizen of the United States, and a resident of Midland, county of Midland, State of Michigan, have invented a new and useful Improvement in Electrolytic Cells, of which the following is a specification, the principle of the invention being herein explained, and the best mode in which I have contemplated 10 applying that principle so as to distinguish it from other inventions.

The present improvements relate more particularly to electrolytic cells of the so-called filter press type, which are characterized by the use of bi-polar electrodes of one kind or another, this construction permitting the passage of a current through a series of cells, or cell compartments, without the necessity of separate electrical connections between successive cells as in the individual type of construction. An electrolytic apparatus of the type in question is shown and described in U. S. Patent No. 1,070,454 to Thos. Griswold, Jr., dated August 19, 1913, and the present invention may be regarded in certain aspects as an improvement thereon.

One object of the present invention is to provide an improved design of bipolar electrode, which will facilitate its construction or assembly in the first place, and also its inspection and repair after installed and in use, while means are also provided whereby any desired cell or cells in a series can be cut out at will without affecting the operation of the series or apparatus as a whole. A further object is to provide improved means for feeding the electrolyte to, as well as withdrawing the same from, the several cells composing the apparatus, whereby the electrolytic operation may be independently controlled in such cells. Still another object is to provide improved means for the collection and removal of the gaseous products of the electrolytic operation.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but

several of the various mechanical forms in which the principle of the invention may be used.

In said annexed drawings:—

Figure 1 is a transverse section of a series of cells constituting an electrolytic apparatus of my present improved type of construction, the plane of the section being indicated by the line 1—1, Fig. 2; Fig. 2 is a front elevational view, *i. e.* a view of the anode side of one of the component sections or frame of such apparatus; Fig. 3 is a similar elevation of the opposite, or cathode, side of such frame or component member; Fig. 4 is a transverse section of such member taken on the plane indicated by the line 4—4, Figs. 2 and 3; Fig. 5 is a similar transverse section of a detail taken on the plane indicated by the line 5—5, Figs. 2 and 3; Fig. 6 is a perspective on a larger scale of one of the individual electrodes carried by such frame; Figs. 7 and 8 are sectional views of a portion of my improved cell illustrating modifications; while Fig. 9 is a diagram showing method of cutting out one or more cells.

The electrolytic cell or apparatus shown in the aforesaid drawings, it should be explained, is more especially designed for the production of caustic and chlorin by the electrolysis of brine, *i. e.* sodium chlorid solution; but it will of course be understood that the apparatus is not limited to use in any particular connection, such as that just stated, and that various features thereof may be susceptible of utilization in a number of different fields.

As in the construction of the electrolytic cell or apparatus, which forms the subject matter of the patent referred to above (No. 1,070,454), the bipolar electrode which characterizes the present construction may be described in a general way as being a composite one, made by inserting or otherwise fixing, in a suitable carrying member a plurality of bipolar carbon electrodes. In the following description the term "electrode" will accordingly be understood to refer to such composite structure, or to the individual electrode, as the context may require. The carrying member may be constructed of any suitable material adapted for the purpose for which the cell is to be used; thus

2
wood, soapstone, slate, glass, stoneware, or the like, may be used in such construction, or preferably the material employed will be a suitable concrete mixture, since this can be 5 readily molded or cast into the form desired and permit the carrying member to remain in one piece. However, it is not to be understood from this that said members may not be assembled of various parts, nor that 10 the latter may not be of different materials. Thus the surrounding or marginal portion 2^a or 2^b of the member may be formed or built up separately from the plate or "board" 1^a or 1^b which actually carries the 15 electrodes, as illustrated for example in Figs. 7 and 8.

In the preferred construction, however, as illustrated in Figs. 1 to 4 inclusive, the carrying member is shown as an integral or 20 one-piece structure, consisting of a flat plate or board 1 marginally surrounded on each edge by a raised flange 2, such flange being somewhat deeper on the anode side than on the cathode side. Rising, preferably 25 centrally, from the upper edge of the frame is what may be termed a hollow head 3, which is in communication with the anode side only of the frame through the medium of ducts 4. This hollow head is also formed 30 in its opposite walls with aligned openings 5 forming a passage for the flow of brine located just above the flange 2 which forms the margin of the member, and with a transverse passageway 6 for the flow of gas in its 35 upper portion separate from the chamber 7 within the main portion of the head. Such passageway 6 communicates with the chamber 7 through a duct or opening 8 and access thereto from the exterior may be had 40 through another opening 9 in the upper edge of the head, which is normally closed by a cap 10 as shown.

Another smaller head 12, formed with a transverse passage 13, also rises from the 45 upper edge of the frame, the passage in this head communicating with the cathode side of the frame through the medium of a duct 14, and being rendered accessible from without through an opening 16 that, like the 50 opening 9 in the larger head, is normally closed with a plug 17.

If desired (although I have not found it necessary in practice) the inner surface of the upper flange on the member on the anode 55 side may incline or slope upwardly slightly from each end of the frame toward the center so that the gaseous product of electrolysis, which collects on this side, will naturally find its way to the ducts 4 and 60 thus escape into the chamber 7 in the larger head. Similarly, the inner surface of the flange on the cathode side of the frame may incline or slope upwardly toward the duct 15, that communicates with the passage 14 65 in the smaller head, from the opposite end of

the frame, so that the gaseous product of electrolysis formed on this, *i. e.* the cathode, side of the frame will be led to the duct and thence to the passage.

For withdrawing liquid from the cathode side of the cell, such liquid being of course caustic soda solution where the electrolyte is sodium chlorid brine, as assumed for the purpose of this description, a tube 20 slidably held in a suitable opening 21 in the bottom flange of the frame near one end of the latter is provided, the lower end of this tube discharging into and being sealed by a suitable troughlike receptacle 22. Obviously, by vertically adjusting such tube, the height 70 at which the liquid on the cathode side of the frame is maintained may be varied as desired. A separate opening 23 is provided at the opposite end of the frame for withdrawing the liquid on the anode side; if 75 found desirable to drain the corresponding chamber, but this opening is plugged as shown, when the cell is in operation. There is also provided a sight glass 24, which rises vertically above the frame, and communicates at its lower end through a suitable aperture 25 with such anode side, whereby the level of the liquid on this side may be observed, it being understood that such liquid, *i. e.* the anolyte, will be maintained 80 at such a height that its level will lie within the chamber 7 in the large head. Means for thus varying the hydrostatic head in the anode compartment are diagrammatically indicated in Figs. 2 and 3.

100 For the purpose of handling, the frame is further provided with oppositely projecting lugs or pins 26 on its respective ends near its upper and lower edges, whereby it may be picked up by means of a crane, or 105 like transporting means, and carried where desired.

Turning now to the construction of the individual electrodes, these will be seen to consist of approximately cylindrical blocks 30 110 of graphite, or other suitable form of carbon, preferably of larger cross-section relatively to the total area of the plate or board 1, in which they are inserted, than are the carbon pins illustrated in the aforesaid patent. 115 These blocks will ordinarily be cast *in situ*, when the frame and board are formed of concrete, but may be removed and other blocks inserted should this be found necessary during the subsequent use of the apparatus. To the ends of the blocks that project on the anode side are secured flat slabs or plates 31 of the same material as said blocks and preferably of rectangular form, the edges of such plates more or less 120 closely approaching each other, so that the anode, in effect, consists of a large composite carbon plate. The separate plates 31 are preferably secured to the corresponding blocks by means of threaded plugs 32 with 125 130

flared heads or pins of similar shape driven in place, such plugs or pins being preferably also formed of carbon.

To the cathode ends of the blocks 30 is secured a metallic (preferably iron) screen 35, such screen being shown as attached to the blocks by means of transversely disposed angle bars 36 welded, or otherwise intimately secured to the screen and then bolted to the adjacent ends of the blocks so as to maintain the screen in good electrical contact with the latter. It will be understood that any other means suited for attaching metal to carbon, such as casting lead about the joint, etc. may be employed. The edges of the screen 35 are received in a shallow recess 37 formed in the adjacent inner edge of the flange on the frame, and such screen is entirely covered over by means of a porous diaphragm 38 the edges of which are tacked to strips 38^a of wood inset in the face of flange 2. The detailed construction of this diaphragm, like the detailed construction of the screen, is not a matter of interest, having nothing to do with the present invention. A gasket 39 of suitable material is interposed at proper places between the juxtaposed faces of successive frames in the assembled condition of the apparatus, to prevent leakage of either gas or liquid.

It will be seen that the screen 35, and the diaphragm 38 thus supported thereby, lie substantially flush with the corresponding face of the frame, whereas the carbon anode plates 31 lie slightly below, or back, of the corresponding face of the frame. Accordingly, when successive frames equipped with electrodes are brought face to face there will be a narrow space in the anode chamber between the plates and screen, across which the electric current passes through the interposed electrolyte.

In such assembled condition of the parts, the liquid to be electrolyzed is maintained at the desired height in the heads 3 by any suitable means, with the result that the anolyte chambers in which such liquid is first received through the corresponding ducts 4, are all full and under a uniform head throughout the apparatus. As the liquid is electrolyzed, it at the same time percolates through the diaphragm 38 and fills the cathode chamber, *i. e.* the space between such diaphragm and the corresponding supporting board 1 or plate, to a height determined by the vertically adjustable tube 20, as previously described. This height, it will be obvious, may be varied in individual cells of the series without respect to the others, in order to secure any desired difference of head between the catholyte and anolyte in each particular cell.

The chlorin which is formed on the anode sides is collected in the chambers 7 in the large heads 3, bubbling up through the

liquor that is being fed through said chambers, so as to maintain the same thoroughly mixed, and thence escapes into the passages 6 in the extreme upper portions of the head, these passages being all in communication 70 and so forming a continuous duct through which the chlorin from all the cells is collected and withdrawn. Similarly, the hydrogen arising from the cathode side of successive cells is received and collected in the 75 communicating passages 13 in the smaller heads 12, whence it is conducted away.

Connected with each of the screens 35, which constitutes in effect the cathode members of the several cells, is a bar 40, preferably of copper, which projects upwardly through the corresponding flange of the frame so as to provide an independent electrical connection with the particular screen-cathode. By attaching a suitable conductor 85 41 to non-adjacent bars, as shown diagrammatically in Fig. 9, the intervening cathodes, and thus the corresponding cells in their entirety, will obviously be cut out, *i. e.* no current will pass therethrough. Such cutting 90 out, or "jumping," of one or more cells may thus be secured, whenever a local breakdown occurs, without it being necessary to throw the entire series or apparatus out of commission pending repairs to an individual cell. 95 When a unit is thus cut out, the cap 10 may be raised to permit opening 8 to be plugged, and the chlorin from the cells beyond will thus be carried through passage 6 without entering the "dead" cell at all. 100

It will be understood that by means of the adjustable tube 20 provided for withdrawing the caustic from the cathode side of the cell, the level of such caustic liquor or catholyte within the corresponding cell section, 105 or compartment, may be lowered to any desired degree, and in fact may be run dry; *i. e.* the only liquid in the cell will be that in the so-called anode chamber, the caustic being withdrawn as rapidly as formed, as is 110 the practice in most cells of individually operated type. It will thus be seen that my present improved cell, while retaining all of the advantages characteristic of the filter press type of construction, nevertheless permits of operation in substantially the same fashion as does the individual type of cell. In addition, by the improved construction of the composite electrode, it is rendered possible to much more conveniently repair or 115 restore a section of the cell, it ordinarily being necessary merely to replace the worn-out sectional plates on the anode side and to put on a fresh diaphragm. By providing means for short-circuiting or cutting out individual cells that may break down, it is possible to keep the series as a whole in operation until the efficiency of the whole apparatus has fallen to the point where it is no longer economical to run the same. 120 125 130

Not only may the plate 1 be separate from the margin 2 of the carrying member, as heretofore described in connection with Fig. 7, but the marginal flanges 45 may be 5 made separately from each other as well as from such plate, as shown in Fig. 8. Such flanges, in other words, whether integral with the plate, or thus separate therefrom, may be more simply designated as separating 10 members, their function being simply to maintain the parts, more especially the plates and screens, in properly spaced relation, and thereby form chambers or compartments for the retention of the electrolyte. 15

By the foregoing construction, I am able, in the first place, to provide a good electrical connection within the apparatus between the anode of one component cell and the metallic 20 diaphragm support that constitutes the cathode of the adjacent cell. In the second place, a greater range of brine head upon the diaphragm is secured, than in prevailing constructions, without, however, increasing 25 the external dimensions of the cell. In this way a better control of the brine flow through the diaphragm is rendered possible. Another advantageous feature is the approximately plane surface of the composite 30 plate anode afforded by the series of separate plates secured to the anode ends of the blocks 30; this, taken in conjunction with the form of cathode employed, insures a more uniform current density throughout 35 the cell, as well as a lower voltage drop through the cell, than in prevailing types of construction. These plates being detachable, it is possible to renew the anodes in any cell unit, when they become worn, without disturbing the blocks that pass through 40 the carrying member. Finally, one or more units may be easily and quickly cut out, should they become defective, without disturbing the remainder of the apparatus or 45 affecting its operation.

Other modes of applying the principle of my invention may be employed instead of the one explained, change being made as regards the mechanism herein disclosed, provided the means stated by any of the following 50 claims or the equivalent of such stated means be employed.

I therefore particularly point out and distinctly claim as my invention:—

55 1. In an electrolytic cell, the combination of two plates supported in spaced relation, the space therebetween being laterally closed to form a chamber for the electrolyte, a metallic screen separating such chamber into compartments, a diaphragm covering said screen, and carbon electrodes projecting through said plates, respectively, one set of electrodes being electrically connected with said screen by direct physical contact.

2. In an electrolytic cell, the combination 65 of two plates and a separating member secured therebetween, whereby a chamber for the electrolyte is formed, a metallic screen separating such chamber into compartments, a diaphragm covering said screen, and carbon electrodes projecting through said plates, respectively, one set of electrodes being electrically connected with said screen by direct physical contact. 70

3. In an electrolytic cell, the combination 75 of two plates supported in spaced relation, the space therebetween being laterally closed to form a chamber for the electrolyte, a metallic screen separating such chamber into compartments, a diaphragm covering 80 said screen, carbon electrodes projecting through said plates, respectively, one set of electrodes being electrically connected with said screen, and means for adjusting the height of the electrolyte within such compartments. 85

4. In an electrolytic cell, the combination 90 of two plates supported in spaced relation, the space therebetween being laterally closed to form a chamber for the electrolyte, a metallic screen separating such chamber into compartments, a diaphragm covering said screen, carbon electrodes projecting through said plates, respectively, one set of electrodes being electrically connected with 95 said screen, and means for adjusting the height of the electrolyte within such compartments independently of each other.

5. An electrolytic cell comprising two bipolar electrodes, and a separating member 100 secured therebetween, whereby a chamber for the electrolyte is formed, said electrodes each consisting of a carrying member of non-conducting material, blocks of conducting material secured therein so as to project 105 on both sides of the same, and a metallic screen separating such chamber into compartments, one set of blocks being electrically connected with said screen by direct physical contact. 110

6. An electrolytic cell comprising two bipolar electrodes, and a separating member secured therebetween, whereby a chamber for the electrolyte is formed, said electrodes each consisting of a carrying member of 115 non-conducting material, blocks of conducting material secured therein so as to project on both sides of the same, a metallic screen separating such chamber into compartments, one set of blocks being electrically connected with said screen by direct physical contact, and a diaphragm covering said screen. 120

7. An electrolytic cell comprising two bipolar electrodes, and a separating member secured therebetween, whereby a chamber 125 for the electrolyte is formed, said electrodes each consisting of a carrying member of non-conducting material, blocks of conduct-

ing material secured therein so as to project on both sides of the same, a metallic screen separating such chamber into compartments, one set of blocks being electrically connected 5 with said screen, a diaphragm covering said screen, and means for adjusting the height of the electrolyte within said compartments.

8. An electrolytic cell comprising two bipolar electrodes, and a separating member 10 secured therebetween, whereby a chamber for the electrolyte is formed, said electrodes each consisting of a carrying member of non-conducting material, blocks of conducting material secured therein so as to project on 15 both sides of the same, a metallic screen separating such chamber into compartments, one set of blocks being electrically connected with said screen, a diaphragm covering said screen, and means for adjusting the height 20 of the electrolyte within said compartments independently of each other.

9. In an electrolytic apparatus of the filter press type, a unit comprising a carrying member of non-conducting material, carbon 25 electrodes secured therein so as to project on both sides of the same, and a metallic screen on one side of said member electrically connected with the corresponding ends of said electrodes in direct physical contact.

30 10. In an electrolytic apparatus of the filter press type, a unit comprising a carrying member of non-conducting material, carbon electrodes secured therein so as to project on both sides of the same, a metallic screen on 35 one side of said member electrically connected with the corresponding ends of said electrodes in direct physical contact, and a diaphragm covering said screen.

11. In an electrolytic apparatus of the filter press type, a unit comprising a carrying member of non-conducting material, carbon 40 electrodes secured therein so as to project on both sides of the same, a metallic screen on one side of said member electrically connected 45 with the corresponding ends of said electrodes, and carbon plates detachably secured to the opposite ends of said electrodes.

12. In an electrolytic apparatus of the filter press type, a unit comprising a carrying 50 member of non-conducting material, carbon electrodes secured therein so as to project on both sides of the same, a metallic screen on one side of said member electrically connected with the corresponding ends of said 55 electrodes, a diaphragm covering said screen, and a plurality of carbon plates respectively detachably secured to the opposite ends of said electrodes.

13. In an electrolytic apparatus of the filter press type, a unit comprising a plate-like 60 carrying member of non-conducting material, a marginal flange on each side of said carrying member for holding the latter in separated relation when assembled together 65 with other carrying members, a plurality of

carbon blocks secured in said carrying member so as to project on both sides of the same, and a metallic screen resting against one of said flanges and electrically connected with the corresponding ends of said blocks in 70 direct physical contact.

14. In an electrolytic apparatus of the filter press type, a unit comprising a plate-like carrying member of non-conducting material, a marginal flange on each side of said 75 carrying member for holding the latter in separated relation when assembled together with other carrying members, a plurality of carbon blocks secured in said carrying member so as to project on both sides of the same, 80 a metallic screen resting against one of said flanges and electrically connected with the corresponding ends of said blocks in direct physical contact, and a diaphragm covering the outer face of said screen. 85

15. In an electrolytic apparatus of the filter press type, a unit comprising a plate-like carrying member of non-conducting material, a marginal flange on each side of said carrying member for holding the latter in 90 separated relation when assembled together with other carrying members, a plurality of carbon blocks secured in said carrying member so as to project on both sides of the same, a metallic screen resting against one of said 95 flanges and electrically connected with the corresponding ends of said blocks, and carbon plates detachably secured to the opposite ends of said blocks.

16. In an electrolytic apparatus of the filter press type, a unit comprising a plate-like carrying member of non-conducting material, an integral marginal flange on each side of said carrying member for holding the latter in separated relation when assembled together with other carrying members, a plurality of carbon blocks secured in 100 said carrying member so as to project on both sides of the same, a metallic screen resting against one of said flanges and electrically connected with the corresponding ends of said blocks, a diaphragm covering the outer face of said screen, and carbon 105 plates detachably secured to the opposite ends of said blocks. 110

17. A series of electrolytic cells made up of a plurality of units each comprising a carrying member of non-conducting material, carbon electrodes secured therein so as to project on both sides of the same, and 115 a metallic screen on one side of said member electrically connected with the corresponding ends of said electrodes in direct physical contact.

18. A series of electrolytic cells made up 120 of a plurality of units each comprising a carrying member of non-conducting material, carbon electrodes secured therein so as to project on both sides of the same, a metallic screen on one side of said member 125 130

- electrically connected with the corresponding ends of said electrodes in direct physical contact, and a diaphragm covering said screen.
- 5 19. A series of electrolytic cells made up of a plurality of units each comprising a carrying member of nonconducting material, carbon electrodes secured therein so as to project on both sides of the same, a 10 metallic screen on one side of said member electrically connected with the corresponding ends of said electrodes, and carbon plates detachably secured to the opposite ends of said electrodes.
- 15 20. A series of electrolytic cells made up of a plurality of units each comprising a carrying member of non-conducting material, carbon electrodes secured therein so as to project on both sides of the same, a 20 metallic screen on one side of said member electrically connected with the corresponding ends of said electrodes, a diaphragm covering said screen, and a plurality of carbon plates respectively detachably secured 25 to the opposite ends of said electrodes.
21. A series of electrolytic cells made up of a plurality of units each comprising a plate-like carrying member of non-conducting material, a marginal flange on each side 30 of said carrying member for holding the latter in separated relation when assembled together with other carrying members, a plurality of carbon blocks secured in said carrying member so as to project on both 35 sides of the same, and a metallic screen resting against one of said flanges and electrically connected with the corresponding ends of said blocks in direct physical contact.
22. A series of electrolytic cells made up 40 of a plurality of units each comprising a platelike carrying member of non-conducting material, a marginal flange on each side of said carrying member for holding the latter in separated relation when assembled 45 together with other carrying members, a plurality of carbon blocks secured in said carrying members so as to project on both sides of the same, a metallic screen resting against one of said flanges and electrically 50 connected with the corresponding ends of said blocks in direct physical contact, and a diaphragm covering the outer face of said screen.
23. A series of electrolytic cells made up 55 of a plurality of units each comprising a platelike carrying member of non-conducting material, a marginal flange on each side of said carrying member for holding the latter in separated relation when assembled 60 together with other carrying members, a plurality of carbon blocks secured in each carrying member so as to project on both sides of the same, a metallic screen resting against one of said flanges and electrically 65 connected with the corresponding ends of
- said blocks in direct physical contact, and carbon plates detachably secured to the opposite ends of said blocks.
24. A series of electrolytic cells made up of a plurality of units each comprising a 70 platelike carrying member of non-conducting material, a marginal flange on each side of said carrying member for holding the latter in separated relation when assembled together with other carrying members, a 75 plurality of carbon blocks secured in each carrying member so as to project on both sides of the same, a metallic screen resting against one of said flanges and electrically connected with the corresponding ends of 80 said blocks, a diaphragm covering the outer face of said screen, and carbon plates detachably secured to the opposite ends of said blocks.
25. In an electrolytic cell of the filter- 85 press type, a unit comprising a plate-like carrying member of non-conducting material, a marginal flange on each side of said carrying member for holding the latter in spaced relation when assembled together 90 with other carrying members, and a hollow head rising above the upper edge of said member, said head being provided in its lower portion with a transverse passage for the flow of brine and with a transverse pas- 95 sage in its upper portion for the flow of gas, the interior of said head being in communication with both such passages and being connected by a duct through the adjacent flange with the space on one side of 100 said member.
26. In an electrolytic cell of the filter- 105 press type, a unit comprising a plate-like carrying member of non-conducting material, a marginal flange on each side of said carrying member for holding the latter in spaced relation when assembled together with other carrying members, a hollow head rising above the upper edge of said member, 110 said head being provided in its lower portion with a transverse passage for the flow of brine and with a transverse passage in its upper portion for the flow of gas, the interior of said head being in communication with both such passages and being connected 115 by a duct through the adjacent flange with the space on one side of said member, and a second hollow head rising above the upper edge of said member, said second head being provided with a transverse passage for the 120 flow of gas connected by a duct through such flange with the space on the opposite side of said member.
27. A series of electrolytic cells made up of a plurality of plate-like units each comprising a plate-like carrying member of non-conducting material, a marginal flange on each side of said carrying member for holding the latter in spaced relation when assembled together with other carrying 125 members.

members, and a hollow head rising above the upper edge of said member, said head being provided in its lower portion with a transverse passage for the flow of brine and with a transverse passage in its upper portion for the flow of gas, the interior of said head being in communication with both such passages and being connected by a duct through the adjacent flange with the space on one side of said member.

28. A series of electrolytic cells made up of a plurality of plate-like units each comprising a plate-like carrying member of non-conducting material, a marginal flange on each side of said carrying member for holding the latter in spaced relation when assembled together with other carrying members, and a hollow head rising above the upper edge of said member, said head being provided in its lower portion with a transverse passage for the flow of brine and with a transverse passage in its upper portion for the flow of gas, the interior of said head being in communication with both such passages and being connected by a duct through the adjacent flange with the space on one side of said member, and means connected with the passages through the lower portions of the heads of said units adapted to supply brine thereto under a variable head.

29. A series of electrolytic cells made up of a plurality of plate-like units each comprising a plate-like carrying member of non-conducting material, a marginal flange on each side of said carrying member for holding the latter in spaced relation when assembled together with other carrying mem-

bers, a hollow head rising above the upper edge of said member, said head being provided in its lower portion with a transverse 40 passage for the flow of brine and with a transverse passage in its upper portion for the flow of gas, the interior of said head being in communication with both such passages and being connected by a duct 45 through the adjacent flange with the space on one side of said member, and a second hollow head rising above the upper edge of said member, said second head being provided with a transverse passage for the flow 50 of gas connected by a duct through such flange with the space on the opposite side of said member.

30. In an electrolytic cell of the filter press type, a unit comprising a carrying 55 member of non-conducting material, blocks of conducting material secured to one side thereof, and a metallic screen attached to the other side of said member and directly electrically connected with said carbon 60 electrodes by suitable conductors through said member.

31. In an electrolytic cell of the filter press type, a unit comprising a carrying member of non-conducting material, carbon electrodes secured to one side thereof, and a metallic screen attached to the other side of said member and directly electrically connected with said carbon electrodes by suitable conductors through said member. 70

Signed by me, this 7th day of December, 1918.

LOUIS E. WARD.
